US0D1088259S

(12) **United States Design Patent** (10) Patent No.: **US D1,088,259 S**
(45) Date of Patent: ** Aug. 12, 2025

(54) **SEX TOY**

(71) Applicant: **EIS GmbH**, Bielefeld (DE)

(72) Inventors: **Alex Dumler**, Hamburg (DE); **Mariana Rosa Yzusqui Burkard**, Hamburg (DE); **Rebecka Rosenlind**, Hamburg (DE)

(73) Assignee: **EIS GmbH**, Bielefeld (DE)

(**) Term: **15 Years**

(21) Appl. No.: **29/898,733**

(22) Filed: **Jul. 31, 2023**

Related U.S. Application Data

(62) Division of application No. 35/514,414, filed on Mar. 17, 2022 (U.S. filing date under 35 U.S.C. 384), and having an international filing date of Mar. 17, 2022, now Pat. No. Des. 1,013,890.

(57) **CLAIM**

The ornamental design for a sex toy as shown and described.

DESCRIPTION

FIG. 1 is a back perspective view of a sex toy;

FIG. 2 is a front view thereof;

FIG. 3 is a top view thereof;

FIG. 4 is a front bottom perspective view thereof;

FIG. 5 is a front top perspective view thereof;

FIG. 6 is a front left perspective view thereof;

FIG. 7 is a back left perspective view thereof;

FIG. 8 is a top left perspective view thereof;

FIG. 9 is a back view thereof;

FIG. 10 is a right side view thereof;

FIG. 11 is a bottom view thereof; and,

FIG. 12 is a left side view thereof.

1 Claim, 12 Drawing Sheets
